United States Patent Office

Des. 220,436

Patented Apr. 13, 1971

220,436

FLAG OR SIMILAR ARTICLE

Edna Ruth Senteney, P.O. Box 460,
Rio Dell, Calif. 95562

Filed Feb. 20, 1970, Ser. No. 21,561

Term of patent 14 years

Int. Cl. D11—05

U.S. Cl. D29—17

The figure is a plan view of a flag showing my new design.

The drawing has been lined for color.

I claim:

The ornamental design for a flag or similar article, as shown and described.
